RUG.

No. 16,832.

Patented Aug. 3, 1886

UNITED STATES PATENT OFFICE.

JULIUS PEGEL, OF CAMDEN, NEW JERSEY, ASSIGNOR TO JOHN BROMLEY & SONS, OF PHILADELPHIA, PENNSYLVANIA.

DESIGN FOR A RUG.

SPECIFICATION forming part of Design No. 16,832, dated August 3, 1886.

Application filed June 19, 1886. Serial No. 205,728. Term of patent 3½ years.

To all whom it may concern:

Be it known that I, JULIUS PEGEL, a subject of the Emperor of Germany, and a resident of Camden, New Jersey, have invented and produced a new and original Design for Rugs, of which the following is a specification, reference being had to the accompanying photographic illustration, to which reference is made.

10 In the illustration one end panel of the design is omitted, as it would be a mere duplication of the end panel shown.

My design consists of the upper and lower longitudinal borders, A A, composed of star-shaped flowers B B and leaves C C. The inner edges of these borders D D form scallops or points, as shown. A description of end panel, E, will suffice for both end panels. This panel has straight upright edges F F, with rectangular lines G G, substantially as shown. Each end (top and bottom) is provided with a terminus, H, formed of scrolls, with a middle cap, I, the latter in general form resembling the fleur-de-lis. The top of the panel has suspended leaves J, and the lower part small begonia-leaves K and small leaves L. The inner edge of the panel is ornamented with small leaves M, and the space between the outer edge of the panel and the edge of the rug is orna-

mented with star-shaped flowers and leaves. 30 The center of the design is ornamented with large and small begonia-leaves N and sprays of small leaves O.

The leading features of the design are the two end panels, substantially as shown, the 35 upper and lower borders of small flowers and leaves, and the center ornamentation, consisting of large and small leaves in form resembling the begonia-leaf.

What I claim is—

40 1. A design for rugs, consisting of the end panels, E, ornamented with large and smaller leaves, with straight sides, and upper and lower scroll ornamentations, upper and lower borders, D D, of leaves and flowers, and the 45 center ornamentation composed of large begonia-leaves, substantially as shown and described.

2. A design for rugs, consisting of the end panels, E, ornamented with large and smaller 50 leaves and separated from the central panel, substantially as shown, said central or large panel being ornamented by large begonia-leaves, substantially as shown and described.

JULIUS PEGEL.
